SHOE INSOLE CONSTRUCTION

John H. McCahan, Canton, Ohio

Application: October 18, 1945; Serial No. 623,043

4 Claims. (Cl. 36—71)

1

The invention relates generally to corrective insoles to be worn in shoes or slippers for relieving foot ailments and for maintaining the foot in a natural and healthy condition. More particularly, the invention relates to an insole having a soft pad or pads shaped and located to protect and relieve the main bearing points of the foot, so as to minimize rubbing and sliding on those points during walking, and at the same time maintain and promote normal functioning of the foot.

Prior insole constructions have included pads for elevating the joints at the heads of some or all of the metatarsals; but I have found that such pads tend to accentuate the rubbing or irritation of the tissue under these points as the foot flexes during walking, with the result that callouses or bunions may form at those points, and callouses or bunions already formed may become more painful.

This condition is more particularly aggravated at the head of the first metatarsal at its joint with the proximal phalange, or at the so-called "ball" of the foot, because a large proportion of the body weight is transmitted to this point. Nature has provided two small rounded sesamoid bones attached to the bottom of the head of the first metatarsal just behind its phalangal joint, and these bones act somewhat as ball bearings as the foot flexes during walking.

I have found that a pad which elevates the insole directly under any of the metatarsal joints tends to accentuate the pressure at that point during walking, and to increase the friction between shoe sole and the bursa or tissue under said joints. Moreover, such an elevated pad tends, I believe, to throw some of the weight to one side and place undue stress on the weaker bones, resulting in the formation of callouses at the joints thereof.

It is a general object of the present invention to provide a novel and improved insole construction which is adapted to protect and pocket the sesamoids so as to relieve friction and rubbing on the foot at that point.

Another object is to provide an insole having a pad for protecting and surrounding the sesamoids on the first metatarsal, and another pad for protecting the phalangal joint at the head of the fifth metatarsal.

A further object is to provide a novel and improved insole which has one or more pads located at or near the phalangal joints of one or more metatarsals in such a way as to minimize friction between the shoe sole and the foot at those points.

Another object is to provide a novel insole which is so constructed and arranged as to minimize friction on the ball of the foot during walking, by causing the sliding of the foot during

2

flexing to occur mainly between the insole and the shoe sole at or under the phalangal-metatarsal joints.

A still further object is to provide a novel and improved insole which has a pad shaped and positioned to pocket the sesamoid bones, and at the same time acting to maintain the foot in proper position during walking.

Finally, it is an object of the present invention to provide a novel and improved shoe insole construction which overcomes the disadvantages of prior constructions, and which is inexpensive to construct and easy to install and use.

These and other objects are accomplished by the parts, constructions, arrangements, and combinations comprising the present invention, a preferred embodiment of which is shown by way of example in the accompanying drawing, and hereinafter set forth in the specification and claims.

20 In general terms, the invention may be set forth as including an insole of a thin piece of leather, and the like, closely conforming to the outline of the heel and arch portion of the shoe sole, and terminating at or near the region of the phalangal-metatarsal joints, the front edge of said insole being skived to gradually slope downwardly to the shoe sole surface, a crescent-shaped soft rubber pad being located on the insole behind and partially around the region below the sesamoids, and a semi-crescent pad being located on the insole behind and under the phalangal joint at the head of the fifth metatarsal.

25 Referring to the drawing in which a preferred embodiment of the invention is shown by way of example,

Fig. 1 is a plan view looking at the upper surface of the improved insole;

Fig. 2 is a side elevation thereof;

Fig. 3 is an enlarged fragmentary cross sectional view as on line 3—3, Fig. 1;

Fig. 4 is a plan view similar to Fig. 1, with the outline of a foot superposed on the insole to show the relative location of the pads and the joints of the foot;

Fig. 5 is a side view of a foot supported on an insole embodying the invention and inserted in a shoe, parts of the shoe being broken away and in section; and

Fig. 6 is a similar view showing the foot and shoe flexed as in taking a step during walking.

Similar numerals refer to similar parts throughout the several views of the drawing.

Referring to Figs. 1, 2 and 3, a preferred embodiment of the insole is indicated generally at 1 and includes a thin flat piece of leather or the like 2 which is cut to have an outline substantially conforming with the outline of the shoe sole on which the insole 1 is to be worn. Thus,

the leather 8 may have a heel portion 9, an arch portion 10 and a front portion 11.

The front portion 11 of the insole 7 is preferably cut along a reverse curve 12 so as to terminate under the region of the phalangal-metatarsal joints of the foot for which the insole is designed. Referring to Fig. 4, it is seen that the curved edge 12 passes substantially under the phalangal-metatarsal joints of the second, third, and fourth metatarsal bones 13, 14 and 15 respectively, and under the rear end of the first proximal phalange 16 in front of its joint with the first metatarsal 17, and under the fifth proximal phalange 18 which is joined to the fifth metatarsal 19.

As shown in Figs. 2 and 3, the front curved edge 12 of the front portion 11 of the insole is skived or gradually tapered as indicated at 20 so as to gradually merge with the upper surface of the shoe sole on which the insole 7 is positioned. The heel portion 9 is provided with means for adhesively attaching the insole to the shoe sole, and as shown such means may comprise the adhesive rubber sheet 21 on the underside of the heel portion 9, which may be in the nature of a vulcanizing patch for repairing an inner tube for a rubber tire.

The improved rubber pad 23 for protecting and pocketing the sesamoid bones 22 is preferably of sponge rubber and is of crescent shape as indicated. The pad 23 is preferably adhesively secured to the underside of the inner sole at a location which will be under the first metatarsal and slightly behind the sesamoids of the foot for which the inner sole is designed, as best shown in Fig. 4. The crescent shape of the pad 23 provides for the ends of the crescent to partially surround the sesamoids 22 so as to form a pocket for the same and protect them from receiving undue pressure from the weight of the body during walking.

If the person wearing the improved inner sole walks normally, that is, substantially straightforwardly, the pad 23 is positioned substantially as shown in Fig. 4 so as to surround the sesamoids an equal amount on both sides. If the person tends to toe inwardly, the pad may be rotated on the insole in a clockwise direction so as to surround the sesamoids on the inner side of the foot to a greater extent and thus cause the foot to turn slightly outwardly in walking. On the other hand, if the person tends to toe outwardly, the pad is rotated in a counter-clockwise direction so as to tend to turn the toes slightly inwardly in walking.

In order to offset any tendency of the foot to shift the body weight toward the outside of the foot because of the crescent pad 23, I prefer to provide a semi-crescent pad 24 on the underside of the insole along its outer edge. The pad 24 is preferably of sponge rubber and constructed similarly to the pad 23, although it may be slightly thinner. The pad 24 is located so as to be under the fifth metatarsal just behind its joint with the fifth proximal phalange 18, and the semi-crescent shape tends to pocket said point and maintain it in proper position during walking. Thus, the semi-crescent pad 24 functions to keep the first metatarsal 17 in balance over the crescent pad 23 much the same as an outrigger on a canoe functions to stabilize the canoe.

In constructing an inner sole embodying the invention, the particular foot which is to wear the inner sole is carefully measured, the outline of the foot obtained, and the relative location of the

sesamoids 22 on the first metatarsal 17 and of the fifth phalangal-metatarsal joint is accurately ascertained, as well as the general location of all of the phalangal metatarsal joints. The inner sole 7 is then cut to conform to the foot outline and its front edge is cut on a reverse curve 12 to follow substantially the region of the joints. The front edge 12 is then skived as shown at 20. The exact location of the sesamoid bones 22 and the fifth metatarsal joint is then plotted on the insole and the pads 23 and 24 located slightly behind these points as shown in Fig. 4.

In locating the pads 23 and 24, due consideration is given to abnormalities of the particular foot being treated, which may require slight shifting of the pads one way or another. Also, the pad 23 is oriented around the sesamoids in the manner previously described to correct a tendency toward toeing inwardly or outwardly.

In the actual operation of the improved insole, the same is secured by means of the adhesive sheet 21 inside the heel of a shoe 25, as indicated in Figs. 5 and 6. The relative position of the large toe 26 is shown within the toe 27 of the shoe, as well as the relative position of the first metatarsal 17 and the sesamoids 22. It will be apparent that as the foot flexes forwardly during walking, from the standing position of Fig. 5 to the position of Fig. 6, the bending of the shoe sole at the ball portion 27' thereof causes the upper surface of the sole to contract longitudinally, while at the same time the bottom portion of the foot at the same location stretches or expands longitudinally to become convexly curved.

This expansion of the underside of the ball of the foot normally causes sliding of the foot at that point on the surface of the shoe sole, and often results in the formation of callouses or bunions, especially where the foot has abnormalities. It is apparent from an inspection of Figs. 5 and 6, that the pad 23 presents a non-skid surface frictionally engaging the shoe sole, so as to form a fulcrum and prevent movement of the inner sole at that point, but that as the shoe sole is bent at 27' and the bursa of the foot below the sesamoids is convexly curved, that part of the insole 11 in front of the pad 23 will expand longitudinally with the bursa so as to cause substantially all of the sliding to occur between the front edge of the insole and the shoe sole. This same sliding action between the front edge of the insole and the shoe sole occurs throughout the width of the marginal edge portion 12 of the insole.

In actual practice, I have observed the underside of the marginal edge portion 12 of numerous insoles embodying the invention which have been worn by various persons, and have noted under 60 surface in every case has become smooth and shiny, showing conclusively that there is sliding action between the front portion of the inner sole and the upper surface of the shoe sole. At the same time, the wearers of the improved insoles have experienced marked relief from pain, callouses and bunions at or near the ball of the foot, after continuous use of the said insole.

Accordingly, it has been demonstrated in actual practice that the crescent shaped pad 23 pockets 70 the sesamoids 22 and relieves pressure thereon, and at the same time provides a fulcrum for maintaining the first metatarsal in proper position during walking and minimizes the friction or rubbing of the shoe sole on the ball of the foot.

The novel and improved insole is inexpensive

to construct and is easily designed for use by any particular foot.

In the foregoing description, certain terms have been used for brevity, clearness and understanding; but no unnecessary limitations are to be implied therefrom beyond the requirements of the prior art, because such words are used for descriptive purposes herein and are intended to be broadly construed.

Moreover, the embodiment of the improved construction illustrated and described herein is by way of example, and the scope of the present invention is not limited to exact details, the constructions comprising the invention, and reasonable mechanical equivalents thereof obvious to those skilled in the art, being set forth in the appended claims.

I claim:

1. A shoe insole including a heel portion and a front portion, said front portion having its front edge shaped to lie under the region of the phalangal-metatarsal joints of a foot supported by said insole, means on the heel portion for adhesively attaching it to a shoe sole, and a crescent-shaped pad located on said insole so as to be partially surrounding and spaced behind the region below the sesamoids of the first metatarsal bone of said foot.

2. A shoe insole including a heel portion and a front portion, said front portion having its front edge shaped to lie under the region of the phalangal-metatarsal joints of a foot supported by said insole, means on the heel portion for adhesively attaching it to a shoe sole, a crescent-shaped pad located on said insole in such position to be partially surrounding and slightly behind the region below the sesamoid bones of the first metatarsal of said foot, and a second pad on said insole in position to be under and slightly behind the region below the fifth phalangal metatarsal joint of said foot.

3. A shoe insole having a curved front edge adapted to lie substantially under the heads of the metatarsals of a foot supported by said in-

sole, the marginal front edge portion of said insole being skived to merge with the surface of a shoe sole supporting said insole, and a crescent-shaped soft rubber pad on the underside of said insole and located behind and partially surrounding the region below the sesamoids of the first metatarsal of said foot, said shoe sole being adapted to slide relative to the front marginal portion of said insole as the foot is flexed within said shoe.

4. A shoe insole having a curved front edge adapted to lie substantially under the heads of the metatarsals of a foot supported by said insole, the marginal front edge portion of said insole being skived to merge with the surface of a shoe sole supporting said insole, means on the heel portion of said insole for adhesively securing it to the heel of said shoe sole, a crescent-shaped soft rubber pad on the underside of said insole and located behind and partially surrounding the region below the sesamoids of the first metatarsal of said foot, and a semi-crescent-shaped pad on the underside of said insole and located below the region behind the fifth phalangal-metatarsal joint of said foot, said shoe sole being adapted to slide relative to the front marginal portion of said insole as the foot is flexed within said shoe.
